Primary Examiner — Lilyana Bekic(74) *Attorney, Agent, or Firm* — Knobbe, Martens, Olson & Bear, LLP(57) **CLAIM**

The ornamental design for a headgear for a patient interface, as shown and described.

DESCRIPTION

FIG. 1 is a front, top and right side perspective view of the headgear for a patient interface in a laid flat non-use configuration.

FIG. 2 is a rear view thereof.

FIG. 3 is a front view thereof.

FIG. 4 is a top view thereof.

FIG. 5 is a bottom view thereof.

FIG. 6 is a left side view thereof.

FIG. 7 is a right side view thereof.

FIG. 8 is a front, top and right side perspective view of the headgear for a patient interface of FIGS. 1 to 7 arranged in an in use configuration to wrap around a user's head.

FIG. 9 is a front view thereof.

FIG. 10 is a rear view thereof.

FIG. 11 is a top view thereof.

FIG. 12 is a bottom view thereof.

FIG. 13 is a left side view thereof; and,

FIG. 14 is a right side view thereof.

1 Claim, 14 Drawing Sheets(56)
